UNITED STATES PATENT OFFICE.

PROSPER L'ORANGE, OF MANNHEIM-FREUDENHEIM, AND LUDWIG GENTZEN, OF SECKENHEIM, NEAR MANNHEIM, REPUBLIC OF GERMANY.

INTERNAL-COMBUSTION ENGINE.

Application filed August 23, 1921. Serial No. 494,524.

To all whom it may concern:

Be it known that we, PROSPER L'ORANGE and LUDWIG GENTZEN, both citizens of Germany, and residing at Mannheim-Freudenheim, and Seckenheim, near Mannheim, Germany, respectively, have invented certain new and useful Improvements in Internal-Combustion Engines, of which the following is a specification.

10 Our invention relates to improvements in internal combustion engines, and more particularly in engines of the type in which the air for supporting combustion is compressed to such a degree that its temperature rises 15 to the point at which the fuel is ignited, and in which an ignition chamber is provided in connection with the cylinder having a member for vaporizing the fuel supplied thereto. One of the objects of the improvements is to provide an engine of this type 20 in which the vaporizing member is not subject to rapid destruction by heat. Another object of the improvements is to provide an engine in which the vaporizing effect of the 25 vaporizer can readily be adapted to the requirements of the fuel supplied to the engine, so that complete vaporization of the fuel is insured and destruction of the vaporizer by excessive heat is avoided. Finally 30 an object of the improvements is to construct the vaporizer relatively to the fuel nozzle in such a manner that all the fuel impinges on the vaporizer proper. With these objects in view our invention consists 35 in the matters to be described hereinafter and particularly pointed out in the appended claims.

For the purpose of explaining the invention a preferred embodiment thereof has 40 been illustrated in the accompanying drawing showing a vertical section of the upper part of the cylinder and its head.

In the example shown in the figure our improved engine comprises a cylinder *a*, a plunger *b*, and a head *c* formed with a cooling jacket *d*, as is well-known in the art. The head *c* is formed with an axial chamber *e* closed by a lid *f* and providing an ignition chamber, and the lid *f* has fitted therein a nozzle *g* for supplying liquid fuel. The chamber *e* is formed with a reduced portion *h* and an axial internally screw-threaded bore *k* the diameter of which is smaller than that of the reduced portion *h*, and which 50 extends through the inner wall of the head 55

and to the explosion chamber *i* of the cylinder.

Within the reduced portion *h* and the bore *k* a vaporizer in the form of a tubular member having a solid bottom is fitted, 60 which member consists of an externally screw-threaded portion *l* screwed into the bore *k* and an outwardly flaring upper portion *p* fitted in the reduced portion *h* and formed with a flange *m* bearing on the inner wall of the cylinder head and smaller in diameter than the reduced portion *h*. The bottom of the portion *l* is provided with passages *n* through which communication is established between the ignition 70 chamber *e* and the combustion chamber *i*. The upper portion of the vaporizer is in the form of a funnel *o*, and it has a close fit with its upper part *p* within the reduced portion *h*, and its upper or front face 75 is flush with the bottom of the chamber *e*. By reason of the conical form of the portion *p* an insulating chamber *q* is provided between the portion *p* and the wall of the reduced portion *h*. As shown, the vaporizing member *p*, *l* is in the form of a bushing fitted in the cylinder head. 80

The operation of the vaporizer is as follows: Upon the compression stroke of the plunger *b* the air for supporting combustion 85 is compressed to 40 atmospheres, so that its temperature is sufficient to ignite the fuel. A part of the compressed air is forced into the ignition chamber *e* and the vaporizer through the passages *n*. Near the end of 90 the compression stroke liquid fuel is thrown through the nozzle *g* into the ignition chamber and on the inner funnel shaped surface *o* of the vaporizer. The jets of air forced into the ignition chamber *e* through the 95 narrow passages *n* meet the liquid fuel projected in the opposite direction, so that the fuel is atomized thoroughly.

The temperature of the vaporizer is sufficient to insure immediate and complete vaporization of the fuel, and the vaporized fuel is immediately ignited, because the temperature of the compressed air is above the ignition temperature of the fuel. From the ignition chamber the ignited gases flow 100 through the passages *n* and into the combustion chamber of the cylinder *a*, where the ignited vapors of fuel are further mixed with air and ignition is continued. 105

An important feature of our invention re- 110

sides in the fact that the burnt gases come in contact only with the inner surface of the vaporizer p , l . They can not reach to the outside thereof because the screw-threaded part l and the upper flange p^1 have a close fit within the cylinder head and the end faces of the parts p and l lie flush respectively with the bottom of the ignition chamber and the inner face of the cylinder head d . Thereby excessive heating of the vaporizer is prevented and a long life thereof is insured.

The insulating chamber q provides suitable means for adapting the temperature of the vaporizer to the character of the fuel, so that immediate and complete vaporization is insured and excessive heating of the vaporizer is avoided. Within the said chamber there is a stagnant mass of air providing effective insulation. By providing vaporizers which, other dimensions being alike, have flanges p^1 of different lengths the contact between the vaporizer and the water-cooled cylinder head can be nicely varied, so that exactly so much heat is withdrawn from the vaporizer, as is necessary to keep the same at the desired temperature. We prefer to supply with each engine a set of vaporizers having flanges p^1 of different dimensions, so that the engineer can select the proper vaporizer according to the character of the fuel, the number of the revolutions, etc. for obtaining the best operation.

We have found that in engines running at high speeds and with less heavy fuel, the natural clearance between the vaporizer and the cylinder head provides sufficient insulation without filling the chamber q with any additional insulating material.

By constructing the portion o internally in the form of a funnel, all the fuel thrown into the ignition chamber through the nozzle g impinges on the vaporizer and not on the wall of the chamber e the temperature of which can not be regulated.

We claim:

1. An internal combustion engine comprising a cylinder having a working chamber, a cylinder head formed with an ignition chamber, a tubular vaporizer interposed between said chambers and having an interior surface flaring toward said ignition chamber, said vaporizer being provided with narrow passages by which it communicates

with the working chamber, and being in peripheral contact with the surrounding walls adjacent to its ends, but out of contact therewith at its intermediate portion so as to form a dead space around such intermediate portion of the tubular vaporizer, and an axially-directed nozzle for throwing a jet of liquid fuel against said flaring interior surface at the entrance end of the vaporizer.

2. An internal combustion engine comprising a cylinder having a working chamber, a cylinder head formed with an ignition chamber, a vaporizer interposed between said chambers and having the peripheral surfaces of both of its ends in tight engagement with the surrounding walls, said vaporizer forming a separate removable element the ends of which thus have tight joints with the surrounding walls, the intervening portion of the vaporizer having its outer surface out of contact with said surrounding walls, and the portion of said walls which surrounds such intervening portion of the vaporizer being imperforate, so that a closed annular chamber is formed around such intervening portion of the vaporizer, and an axially-directed nozzle for injecting fuel into said ignition chamber and against the inner surface of the vaporizer.

3. An internal combustion engine comprising a cylinder having a working chamber, a cylinder head formed with an ignition chamber, a vaporizer interposed between said chambers and communicating with both of them, said vaporizer constituting a separate removable element having an inner surface flaring toward the ignition chamber at that end of the vaporizer which communicates with said ignition chamber, said end of the vaporizer being fitted into, and in tight peripheral contact with, the surrounding wall, and the other end of the vaporizer likewise being in tight contact with the surrounding wall, so that the outer surface of the vaporizer, between said ends, can not be reached by the gases of either the ignition chamber or the working chamber, and an axially-directed nozzle for throwing a jet of liquid fuel against said flaring inner surface at the entrance end of the vaporizer.

We testimony whereof we hereunto affix our signatures.

PROSPER L'ORANGE.
LUDWIG GENTZEN.
